UNITED STATES PATENT OFFICE.

LOUIS MANDEL, OF CHICAGO, ILLINOIS.

BEZEL AND METHOD OF CONSTRUCTION THEREOF.

No. 907,156.

Specification of Letters Patent.

Patented Dec. 22, 1908.

Application filed December 12, 1907. Serial No. 406,214.

To all whom it may concern:

Be it known that I, LOUIS MANDEL, a citizen of the United States, residing at Chicago, in the county of Cook and State of Illinois, have invented certain new and useful Improvements in Bezels and Methods of Construction Thereof, of which the following is a description, reference being had to the accompanying drawings, forming a part of this specification, in which corresponding letters of reference in the different figures indicate like parts.

The object of my invention is to provide a cheap and simple bezel for miniatures, brooches and other analogous devices, all of which is hereinafter more particularly described and definitely pointed out in the claims.

In the drawings, Figure 1 is a face view of a sheet-metal blank representing the first step in the formation of a bezel, Fig. 2 is a like view thereof as it would appear after having been cupped, Fig. 3 is a transverse, vertical sectional view of Fig. 2, Fig. 4 is a bottom view of the device as it would appear after having undergone the operation of swaging to form a shoulder thereon against which to rest a ring, Fig. 5 is a central vertical sectional view thereof, Fig. 6 is a like view showing the addition of the ring thereto, Fig. 7 is a view corresponding to Fig. 6 showing the further step of swaging the annular flange to secure the ring in place, Fig. 8 is a face view of the finished bezel, and Fig. 9 is a central vertical sectional view thereof showing the miniature or other article which it is designed to protect secured therein.

Referring to the drawings, *a* represents, generally, a circular sheet-metal blank having a body portion *b* and lugs *c* extending outwardly from its periphery. Said blank may be cut by hand or by means of a suitable die, after which it is swaged, preferably by means of dies, so as to form an annular flange *d*, Figs. 2 and 3, thereon.

To the extent described, the method, as well as the product, is old and well known; and it has heretofore been customary to place a ring around the cylindrical portion formed by the flange *d* and to secure said ring in place by soldering it directly to the flange. This is not only a slow and expensive operation, but often results in irreparable injury to the article formed; and it is to avoid this expense and risk that my improved method has been devised. Instead, therefore, of

leaving the flange *d* in cylindrical form as shown in Figs. 2 and 3 and soldering a ring thereon, I first swage said flange so as to expand the same next to the body *b*, to form a shoulder or bead *e* thereon of larger diameter than the remaining portion of the flange, as clearly shown in Figs. 4 and 5. This may be accomplished by hand by placing within the cup a mandrel having a peripheral bead at its end, and striking the flange by means of a hammer or counterpart tool until it assumes the form shown, or it may be formed by placing a ring around that portion of the flange *d* which is not to be expanded and then operating an expanding mandrel or hand tool within the remaining portion so as to spread it in the manner described. When the bead *e* is formed, I then place over the flange *d* a ring *f* of an inner diameter corresponding to the outer diameter of the unexpanded portion of the flange, said ring resting against the shoulder *e* as clearly shown in Fig. 6. When the ring *f* is in place, I then expand the outer edge of the flange *d* as shown at *g*, Fig. 7, against the ring *f*, thereby forming an annular groove around the flange into which is firmly and securely fitted the ring *f*. The expansion described may be accomplished by means of a hand tool by means of which said flange is pressed outwardly against the ring, or a spreading circular tool or die may be forced into the flange to form it into the required shape.

When the swaging last described is accomplished, a predetermined portion of the body *b* is cut from the blank, preferably by means of a cutting die, which may be so formed as to bevel or bend inwardly the remaining annular portion as shown at *h*, Figs. 8 and 9. When this is accomplished, the article *i*, Fig. 9, to be inclosed within the bezel and protected thereby may be secured in place by means of the lugs *c* which are intended to be bent as shown in said last named figure. A securing pin *j*, of any well known form, may be attached to the back of the article inclosed within the bezel.

I am enabled by means of my improved method, to not only greatly reduce the cost of manufacture, but to make a product of superior excellence both in durability and appearance.

Having thus described my invention, I claim:

1. As an improved article of manufacture, a sheet metal bezel having a peripheral

groove formed therein, in combination with a non-elastic ring permanently embedded in said groove.

2. The combination with a sheet-metal
5 bezel having a peripheral groove, of a non-
yielding ring embedded within said groove
and held rigidly in place by the adjacent
walls thereof.

In testimony whereof, I have signed this
specification in the presence of two subscrib- 10
ing witnesses, this tenth day of December
1907.

LOUIS MANDEL.
